LESLIE A. RAWSON, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

DOUBLE LEG CONSTRUCTION FOR DERRICKS WITH EQUALIZING MEANS

Application filed April 19, 1930. Serial No. 445,631.

My invention relates to a derrick such as is employed in the oil producing industry, having double leg constructions extending between the base of the derrick and the crown thereof. The invention relates to an invention similar to that disclosed in my copending application entitled "Double leg construction for derrick" filed April 23, 1930, Serial No. 446,555. Derricks of this character form part of the prior art, and the broad idea of a derrick having double leg constructions does not of itself constitute my present invention.

In such derricks referred to, the load is proportioned on the primary and secondary legs of each double leg construction by a manually operable means, and due to the reliance on the guesswork of the workman for proportioning the load it is never known whether or not the load is properly distributed on the legs. One of the common double leg constructions provides an adjustment means in one of the legs whereby the leg may be lengthened and thus caused to carry a part of the load of the crown. The workman usually operates the lengthening means until he thinks that the load is properly distributed. On many occasions the workman's judgment has been greatly in error and intense strains have been placed on one of the legs to the injury of the derrick.

My invention provides a double leg construction for a derrick in which the primary and secondary legs are automatically caused to carry predetermined proportions of the load carried by the crown of the derrick; and it absolutely eliminates the human element which is involved in the making of the adjustments in the derricks of the prior art.

In the derrick of my invention a predetermined proportion of the load carried by the primary and secondary legs never varies throughout the use of the double leg construction in the derrick. Due to an equalizing means which constitutes a part of my invention, any slight distortion or settling of the derrick will not impair the operation of the legs, nor will it change the proportions of the weight carried by the primary and secondary legs.

The equalizing means referred to is posi-

tioned relative to the other parts of the derrick so that the load is transmitted through this equalizing means. The equalizing means automatically positions itself so that it places the proper load on the primary and secondary legs and during the use of the derrick will maintain the proper proportions of the load.

Other advantages of my invention and the important features will be pointed out in the following description in which two forms of my invention are illustrated.

In the accompanying drawings,

Fig. 1 is an elevational view illustrating a derrick incorporating the features of my invention.

Fig. 2 is a horizontal cross section taken on the line 2-2 of Fig. 1.

Fig. 3 is an elevational view in section showing a double leg construction of my invention in which the equalizing means is in the upper end of the derrick.

Fig. 4 is an enlarged sectional view showing the equalizing means of Fig. 3.

Fig. 5 is a section taken on the line 5-5 of Fig. 4.

Fig. 6 is a section taken on the line 6-6 of Fig. 4.

Fig. 7 is a section taken on the line 7-7 of Fig. 4.

The derrick in which my invention is incorporated has a base construction 11, a crown construction 12, and a plurality of double leg constructions 14. According to usual derrick practice there is a double leg construction placed in each corner of the derrick, and each leg construction extends from a corner of the base construction 11 to a corner of the crown construction 12. In view of the fact that the four leg constructions 14 are identical both in construction and operation, in the ensuing description I will describe but one double leg construction, but it is to be understood that the description applies equally well to the other three leg constructions of the derrick.

Referring particularly to Figs. 3 and 7, each leg construction includes a primary leg 16 which is preferably made from an angle bar and installed in the derrick with the

flanges of the angle bar extending parallel to the sides of the base construction 11 and the crown construction 12 which are of rectangular shape. The lower end of the primary leg 16 extends into a corner member 18 of the base construction 11 and is rigidly secured thereto by suitable bolts 19. The upper end of the primary leg 16 extends within a headpiece 20 of the crown construction 12, there being a headpiece 20 arranged at each corner thereof. The headpiece 20 includes a pair of upright walls 21 which extend perpendicularly to each other and which are engaged by the flanges of the primary leg 16. The primary leg 16 is held in position against the upright walls 21 by bolts 23 which extend through vertically elongated slots 24 of the primary legs 16 and also through openings provided in the upright walls 21.

20 A secondary leg 25, which forms a part of the double leg construction 14, is preferably tubular in cross section and is conveniently positioned within the primary leg 16, as best shown in Fig. 7. The secondary leg may be retained in this position by suitable holding devices 26. The lower end of the secondary leg is provided with a head 29 which rests in a socket 30 provided by the corner piece 18.

25 Referring to Fig. 4, the upper ends of the primary and secondary legs are provided with a semi-spherical bearing member 35 and a semi-cylindrical bearing member 36 respectively. These bearing members 35 and 36 are adapted to be seated in a semi-spherical seat 37 and a semi-cylindrical seat 38 respectively of an equalizing or load proportioning member 39. The equalizing member 39 has an upper semi-spherical bearing face 41 which seats on a semi-spherical seat 42 provided by the headpiece 20. The semi-spherical bearing face 41 and seat 42 are generated around a point 43 which is substantially the same horizontal plane X—X as the centers 44 and 45 around which the bearing faces of the bearing members 35 and 36 are generated. The point 43 is the fulcrum point around which the equalizing member 39 swings. The weight of the crown is applied from the crown to the equalizing member 39 and from the equalizing member 39 to the primary and secondary legs 16 and 25, and the load is distributed to the two legs according to the respective lengths of the lever arms A and B. It will be seen that the relative loads carried by the two legs are predetermined by the relative lengths of the lever arms A and B, and it will further be seen that by designing the equalizing member to have different relative lengths of lever arms, the distribution of the load will be different.

60 For the purpose of loosely connecting the equalizing member 39 to the headpiece 20, I provide the equalizing member 39 with depending lugs 47 having vertically elongated

openings 48 through which a retaining bar 49 is extended, this retaining bar 49 being held by side walls 50 of the headpiece 20. The depending lugs are provided with vertically elongated openings in order that there will be no interference to all of the load being transferred from the headpiece to the equalizing member through the engagement of the seat 42 and the face 41.

70 The equalizing member 39 is provided with the extensive bearing face in order that it may be fully capable of transferring the enormous loads to the legs of the derrick. This bearing face is made cylindrical in order that the equalizing member will swing around a horizontal axis on which the point 43 is located. The upper end of the primary leg and the equalizing member are provided with semi-spherical bearings in order that the equalizing member may freely adjust itself to compensate for any slight misalignment of either of the legs. If desired, both bearing members 35 and 36 may be semi-spherical.

75 I consider my invention to be broadly novel in the provision of a derrick having a double leg construction in combination with means for automatically imposing a predetermined proportion of the load on each leg.

80 My invention is further novel in the provision of an equalizing means which is balanced by the weight imposed on the legs, and by virtue of this balancing action the equalizing means places a predetermined proportion of the load on the two legs.

85 I claim as my invention:

1. In a derrick, a base construction, a crown construction, a leg construction extending between said base construction and said crown construction, said leg construction including a pair of legs, the combination of: an equalizing means interposed in the derrick structure through which the load carried by the crown construction is transmitted, said equalizing means engaging said legs and proportioning the amount of said load carried by each of said legs.

90 105 110 115 120 125 130

2. In a derrick, a base construction, a crown construction, a leg construction extending between said base construction and said crown construction, said leg construction including a pair of legs, said legs being adapted to transmit from said crown construction to said base construction the load carried by said crown construction, the combination of: an equalizing means supported by one of said constructions and fulcruming thereon, said legs engaging said equalizing means on opposite sides of said fulcrum.

3. In a derrick of the class described the combination of: a crown structure; leg means including a plurality of legs whereby said crown structure is supported; and load distributing means operative to automatically proportion the load on said legs upon the

application of the load on said crown structure.

4. In a derrick of the class described the combination of: a primary leg; a secondary leg; a crown structure; and means through which the load is transmitted for automatically imposing a predetermined proportion of the load on each of said legs.

5. In a derrick of the class described the combination of: a primary leg; a secondary leg; a crown structure; and means engaging each of said legs and said crown structure for automatically imposing a predetermined proportion of the load on each of said legs.

15 6. In combination with a primary leg, a secondary leg, and a thrust receiving member of an oil well derrick: a thrust dividing device adapted to receive thrust from said member and divide said thrust in definite proportions between said legs.

20 7. In combination with a primary leg, a secondary leg, and a thrust receiving member of an oil well derrick: a lever fulcrumed on said member and engaging each of said legs 25 at a definite distance from the fulcrum so that the thrust of said member is divided in definite proportions between said legs.

8. In combination with a primary leg, a secondary leg, and a thrust receiving member of an oil well derrick: a lever fulcrumed on said member and engaging each of said legs at a definite distance from the fulcrum so that the lever may rock about the fulcrum and divide the thrust thereon in definite proportions 30 between said legs.

25 9. In a derrick construction, the combination of: a primary leg; a secondary leg; a thrust member; and a swingable lever engaging said primary and secondary legs and said thrust member for proportioning the load of the derrick between said primary and secondary legs.

10. In a derrick construction, the combination of: a primary leg; a secondary leg; a thrust member; and a swingable lever engaging said primary and secondary legs and fulcrumed on said thrust member for proportioning the load of the derrick between said primary and secondary legs.

50 11. In a derrick construction, the combination of: a primary leg; a secondary leg; a thrust member; and a swingable lever engaging said primary and secondary legs and swingable on said thrust member for proportioning the load of the derrick between said primary and secondary legs.

55 12. In a derrick construction, the combination of: a primary leg; a secondary leg; a thrust member; and load proportioning means disposed between said primary and secondary legs and said thrust member, said load proportioning means being automatically adjustable in position for proportioning the load of the derrick between said primary and secondary legs.

13. In a derrick construction, the combination of: a primary leg; a secondary leg; a thrust member; and load proportioning means disposed between said primary and secondary legs and said thrust member, said load proportioning means being movable with respect to said primary and secondary legs and being automatically adjustable in position for proportioning the load of the derrick between said primary and secondary legs.

14. In a derrick construction, the combination of: a primary leg; a secondary leg; a thrust member having a fulcrum seat; and a lever engaging said primary and secondary legs, and engaging said fulcrum seat.

15. In a derrick construction, the combination of: a primary leg; a secondary leg; a thrust member having an arcuate fulcrum seat; and a lever engaging said primary and secondary legs, and having an arcuate face engaging said arcuate fulcrum seat.

16. In a derrick construction, the combination of: a primary leg; a secondary leg; a thrust member; load proportioning means disposed between said primary and secondary legs and said thrust member, said load proportioning means being automatically adjustable in position for proportioning the load of the derrick between said primary and secondary legs; and means for holding said load proportioning means in place.

17. In a derrick construction, the combination of: a base construction; a crown construction; a primary leg extending between said constructions; a secondary leg, extending between said constructions; and lever means engaging said primary and secondary legs and one of said constructions for distributing the load of said derrick between 100 said legs.

18. In a derrick construction, the combination of: a base construction; a crown construction; a primary leg extending between said constructions; a secondary leg extending between said constructions; and lever means fulcrumed on one of said constructions and engaging said primary and secondary legs on opposite sides of the fulcrum for distributing the load of said derrick between 105 said legs.

In testimony whereof, I have hereunto set my hand at Los Angeles, California, this 10th day of April, 1930.

LESLIE A. RAWSON. 110
